UNITED STATES PATENT OFFICE.

LEONARD E. BUMPASS, OF DALLAS, TEXAS.

MEANS FOR PROTECTING VAULTS.

1,374,055.

Specification of Letters Patent.

Patented Apr. 5, 1921.

Application filed August 16, 1920. Serial No. 403,739.

To all whom it may concern:

Be it known that I, LEONARD E. BUMPASS, a citizen of the United States, residing at Dallas, in the county of Dallas and State of Texas, have invented certain new and useful Improvements in Means for Protecting Vaults, of which the following is a specification, reference being had therein to the accompanying drawings.

10 The present invention relates to means for protecting vaults and the like from robbery by burglars. Broadly stated the invention resides in providing a plurality of frangible receptacles of such shape and so arranged 15 as to constitute an inner lining for the wall of the vault to be protected, with the inner sides of said frangible containers protected against breakage by accident and with the outer sides thereof exposed toward the vault 20 wall so that any attempt to penetrate the wall from the outside will result in rupturing one or more of said containers and releasing an asphyxiating or other disabling gas.

25 In the accompanying drawings:

Figure 1 is a sectional perspective view illustrating my method of protecting the walls of a vault;

30 Fig. 2 is a detail perspective view of one of the elements illustrated in Fig. 1;

Fig. 3 is a sectional view showing the same construction as illustrated in Figs. 1 and 2;

Fig. 4 is a horizontal sectional view illustrating a modified section; and

35 Fig. 5 is a detail perspective view of a metal stud employed in conjunction with the structure illustrated in Fig. 4.

Like numerals designate corresponding parts in all of the figures of the drawing.

40 A very large percentage of bank vaults in small towns and country places are built of brick and these vaults can be easily entered by removing some of the brick. I propose to reline these brick vaults with gas con-

45 tainers disposed in such relation to the walls of the vault that the blows necessary to remove the bricks will result in fracturing one or more of the containers and permitting the escape of the asphyxiating or other disabling

50 gas. As this description proceeds it will be seen that a structure is provided which will accomplish the foregoing objects, while at the same time the possibility of breakage of any of said containers by the employees of 55 the bank is effectually guarded against.

To secure the aforesaid results, I propose

to employ a plurality of metal shells adapted to receive frangible gas containers, said shells being provided upon one side with means for engaging the brick wall of the 60 vault and being provided upon the other side with plaster retaining elements so that the vault may be finished with an inside coat of cement plaster and the glass containers will be disposed toward the bricks. 65 The shells not only prevent accidental breaking of the gas containers when the latter are in place but they serve as holders to prevent accidental breakage of the containers during the building of the vault and during the 70 time that new vaults are being lined or old vaults are being relined.

Referring now to Figs. 1, 2 and 3, 12 designates a preferably sheet metal shell, a plurality of these being used in the lining 75 of the wall 13 of the vault 14. These shells are preferably provided with projections of some form indicated at 15 adapted to project between the courses of brick of which the wall is formed and to be embedded in 80 the plaster. Glass containers 16 are held within the shells and are disposed toward the bricks of the wall. Thus the inner vertical surfaces 12^a of the shells completely 85 overlie and protect the containers and prevent accidental breakage of the same. To hold the containers 16 firmly in the shells, the shells are provided with projections 17 adapted to engage in recesses 18 formed in the containers 16. Thus accidental dropping 90 of the containers from the shells during the time that the latter are being handled by masons in the building and relining of the wall is effectually guarded against. I preferably provide upon the inner vertical faces 95 12^a plaster engaging and retaining projections 19, so that after the wall is built and lined an inner finishing and protecting coating of cement plaster, indicated at 20, may be placed over the entire surface of the wall. 100

In the form of the invention illustrated in Figs. 4 and 5 metallic studs 21 are employed. These studs have rearwardly projecting members 22 adapted to project between the courses of brick and said members 105 are provided with sinuous portions 23 which engage with the plaster and prevent outward movement of the studs with respect to the wall. These studs have two rows of projections along their outer edges, the inner row of projections indicated at 23 serves 110 to engage over and retain frangible contain-

ers 24 which are disposed toward the bricks. The outer row of projections 25 are thus caused to lie in spaced relation to the adjacent faces of the containers to thereby permit the plaster 26 to engage behind these projections.

It is to be understood that the showing in the accompanying drawings is merely illustrative. It is manifest that many different types of containers for the gas could be provided and that many different types of protecting shells could be devised to hold these containers. It is only necessary that these shells be adapted to engage the wall upon the one side and support plaster upon the other and any structure that will do this comes within the scope of the invention.

Having described my invention, what I claim is:

- 20 1. The combination with a vault comprising a masonry wall, of an inner liner for said vault wall comprising a plurality of frangible gas containers disposed in contact with the inner side of said wall.
- 25 2. In a structure as recited in claim 1 the combination with a plurality of protecting shells for said containers, said shells being provided with means for engaging the masonry wall.
- 30 3. The combination with a vault having a masonry wall, of a plurality of gas containers and a plurality of protecting shells

for said containers each of said shells comprising elements upon its inner sides for engaging with the masonry wall and elements upon its outer sides for engaging and retaining plaster.

4. In a device of the character described the combination with a vault comprising a masonry wall, of a plurality of frangible gas containers and a plurality of retaining elements for said gas containers, said retaining elements comprising means adapted to engage the masonry wall, means for holding the containers in place and means for engaging and retaining plaster.

5. In a device of the character described the combination with a vault comprising a brick wall, of a plurality of frangible gas containers constituting a lining for the inner face of said wall, and a plurality of retaining elements for the said gas containers comprising sheet metal shells which cover the outer faces of the gas containers, the inner faces of the gas containers lying directly against the brick wall, horizontally projecting elements carried by the said shells which project between the courses of brick and engage the plaster therein and plaster engaging elements formed upon the outer faces of said shells.

In testimony whereof I hereunto affix my signature.

LEONARD E. BUMPASS.
